UNITED STATES PATENT OFFICE.

ALFRED J. SCHAUB, SR., OF OAKLAND, CALIFORNIA.

ENVELOPE MOISTENER.

Application filed October 28, 1921. Serial No. 511,164.

To all whom it may concern:

Be it known that I, ALFRED J. SCHAUB, Sr., a citizen of the United States, and a resident of Oakland, county of Alameda, and State 5 of California, have invented a new and useful Envelope Moistener, of which the following is a specification.

The present invention relates to improvements in envelope moistening devices and is 10 designed for the purpose of facilitating the work of sealing envelopes in large quantities. A particular object of my invention is the combination of means for opening the envelope with the moistening means and the 15 means for draining surplus moisture from the envelope after the latter has passed the moistening means. A further object of my invention is to provide means of the character described which can be cheaply constructed 20 and is economical in its use.

With these objects in mind I have shown the preferred form of my device in the accompanying drawing, in which Figure 1 represents a side elevation of my device; Figure 25 2 a vertical cross section through the same along line 2—2 of Figure 1; Figure 3 a top plan view of the same, the position of an envelope being shown in dotted lines, and Figure 4 an enlarged sectional detail view along 30 line 4—4 of Figure 3.

While the drawing shows the preferred form of my invention only, it will be readily understood that slight changes or modifications may be made without departing from 35 the spirit of the present invention.

My device rests on the base (1) and comprises a box (2) which may be partly filled with water and which has a frame structure (3) therein provided with two axially aligned 40 bearings (4) in which revolves the shaft (6) supporting the drum (7). The drum is covered with a layer (8) of wick fabric or similar material and is positioned in such a way that its upper part slightly projects over the 45 cover (9) of the box, a hole (11) in the cover (9) allowing the drum to extend through the cover. The latter is secured to the box by means of the hinges (12) and is provided with an upwardly curved extension (14), a 50 slight pressure on the latter extension being sufficient to turn the cover on its hinges so as to open the box.

To use my device the operator will take an envelope to be sealed, place the right side of 55 the margin of the flap on the drum which has been previously moistened and then pull the

envelope from left to right so that the edge portion of the flap passes over the drum and receives moisture from the same. This being the main principle of my device, I provide 60 several auxiliary means for facilitating this operation. One of these means consists in a simple device for opening the envelope which it is assumed is loosely folded. The cover (9) is provided at the end opposite its hinges 65 with a projection (16) slightly curved downwardly as shown in Figure 1 and rounded off as shown in Figure 3. Over this projection extends the free end of a spring (17), the other end of which is secured to the box 70 in any convenient manner. If the loosely folded envelope is inserted between the spring and the projection, approaching the same from the left hand side the projection, while passing underneath the body portion 75 of the envelope, will engage the flap and force its way between the flap and the envelope, and as the envelope is further advanced the flap coming in contact with the edge of the projection will be slowly forced into the 80 plane of the envelope so that the flap is now open and ready to pass over the drum to receive its moisture. It is understood that in the ordinary envelope commonly used only 85 the edge of the flap is provided with glue and that it is desired to confine the moisture to that portion. To accomplish this I provide a small arc (18) on the near side of the drum. The arc as shown in Figure 1 is slightly higher than the drum and the body portion of the 90 envelope having to pass over this arc is kept out of contact with the drum so as to remain 95 perfectly dry.

The drum rotates with the envelope and in doing so passes through the water in the 95 box, thus receiving a constant supply of new moisture. In many cases the flap of the envelope might receive more moisture than is necessary for the sealing of the envelope. Since this is undesirable I provide a means 100 for draining the surplus moisture from the flap before the latter is sealed, which consists of an inclined plate (19) secured on the cover of the box in such a manner that the flap after passing the drum has to pass over 105 the same, and I further provide a spring (21) which extends over the top edge of the inclined plate and which is adapted to press down on the envelope flap passing over the inclined plate. The spring (21) 110 is provided with a longitudinal slot (22) running parallel to the top edge of the in-

clined plate which makes it possible to position the spring somewhat lower than could be done otherwise so that the two edges (23) and (24) defining the slot are almost on a level with the top edge of the inclined plate and that the flap forced between the plate and the spring is pressed downwardly by the two edges (23) and (24) on both sides of the top edge of the inclined plate as shown 10 in Figure 4, whereby surplus moisture is drained from the flap in a most effective manner.

To press the flap passing the drum firmly against the same so that it will absorb moisture I provide a weight (26) which is pivotally supported on the arm (27) pivoted in the bracket (28) secured to the side of the box in any manner desired. The weight in its active position lies on the peripheral surface 20 of the drum and the envelope flap to be moistened has to pass between the weight and the drum and will naturally be pressed against the drum by the weight while lifting the same.

25 I claim:

1. An envelope moistening device comprising a rotatably mounted moistening drum, a self-adjusting contact maintaining member co-operating therewith, means for 30 opening the envelope flap and means for removing surplus moisture associated therewith so as to allow of the insertion of the folded envelope and the opening, moistening and draining of the flap in one continuous operation.

2. An envelope moistening device comprising a rotatably mounted moistening drum, an arched support for the body portion of the envelope flap mounted in opera-

tive proximity thereto, a self-adjusting contact maintaining member co-operating with the drum, means for opening the envelope flap and means for removing surplus moisture associated with the drum so as to allow of the insertion of the folded envelope and 45 the opening, moistening and draining of the flap in one continuous operation.

3. In an envelope moistening device, a rotatably mounted moistening drum and a surplus moisture draining means associated therewith, said means comprising a plate member declining toward the drum having a spring member co-operating with its top edge for pressing the moistened envelope 50 against the said edge.

4. In an envelope moistening device, a rotatably mounted moistening drum and a surplus moisture draining means associated therewith, said means comprising a plate member declining toward the drum having a slotted spring member co-operating with the top edge so that the two edges defining the slot bend the passing envelope around 55 the top edge of the plate member.

5. In an envelope moistening device, a rotatably mounted moistening drum and an envelope opening means operatively associated therewith, said means comprising a thin projection mounted in operative proximity to the drum adapted to force itself between the flap and the body of the envelope and a spring mounted over the projection for holding the body portion against the projection whereby the flap is forced in the same plane with the body portion on guiding the envelope toward the drum.

ALFRED J. SCHaub, Sr.
